UNITED STATES PATENT OFFICE.

ARTHUR J. CURREN, OF ELYRIA, OHIO.

AUTOMATIC TELEPHONE-DIAL SUPPORT.

Application filed October 20, 1919. Serial No. 331,967.

To all whom it may concern:

Be it known that I, ARTHUR J. CURREN, a citizen of the United States, residing at Elyria, in the county of Lorain and State of Ohio, have invented certain new and useful Improvements in Automatic Telephone-Dial Supports, of which the following is a full, clear, concise, and exact description.

My invention relates to automatic telephone dial supports, and particularly to that type of support which is adapted to secure an automatic telephone sending dial to the casing of a wall telephone.

It is an object of my invention to provide such a support of the pendant type, wherein the automatic dial is presented at the lower front portion of the instrument, in inclined position, relative to the front of the wall telephone casing.

It is a further object of my invention to provide such a support with a cup-shaped member, to which the dial may be conveniently secured, and which cup-shaped member will exclude dust and dirt from the working parts of the dial inclosed in the cup-shaped member and to furthermore provide a channel shaped support for the said cup-shaped member, preferably of reduced cross section, whereby the cup-shaped member may be secured to the bottom of the wall telephone casing, the channel member at the same time serving to inclose and thereby protect the electrical circuit conductors leading from the wall telephone casing to the telephone dial mechanism.

Further objects of my invention include the provision of the support which is adapted to be cheaply manufactured of sheet steel stampings which may be readily spot-welded together, forming a unitary rugged integral structure which is light in weight, and which may be readily secured in place on the lower wall of a telephone, and in which the dial may be properly supported in proper angular position.

Other objects of my invention and the invention itself will be better understood by referring to the drawings accompanying this specification and in which drawings:

Fig. 1 shows a front view of a wall telephone, to which is secured an automatic telephone dial by means of the improved support of my invention; in this view the support itself is not visible being hidden by the dial;

Fig. 2 shows a side cross sectional view of

the dial support of my invention, together with a fragment of the wall telephone casing, the automatic telephone dial being indicated in dotted lines to show its relative position;

Fig. 3 shows a rear view of my improved dial support, only;

Fig. 4 shows an end cross-sectional view of my improved support taken on a line 4—4 indicated in Fig. 3, looking in the direction of the indicating arrows.

The cross-sectional view illustrated in Fig. 2, is that view which would be had taken on a line 2—2 of Fig. 3 looking in the direction of the indicating arrows.

Referring now to the figures in each of which corresponding parts are indicated by like reference characters, at 11, is shown a telephone casing having a front wall 12, and a bottom wall 13. Prior to the mounting of the dial support on the telephone, a hole 14, is drilled in the telephone casing bottom wall 13; for the passage of electrical conductors 15, which connect the dial mechanism with the telephone circuits. The dial support is made from two sheet metal stampings, the one, 16, having the form of a cup, and which is adapted to carry the dial 17 on its outer rim, the other being the channeled member 18, having an upper winged portion 19, an intermediate channeled portion 20 and a lower cup supporting portion 21. The winged portion 19, and the cup supporting portion 21, are formed as a flange of the channeled portion 20, the portion 19 and the portion 21 being connected by an intermediate flange portion 31. The upper flange portion 19, is disposed at an angle of approximately 60 degrees although this may be varied as desired, to the plane of the flange portion 31. The flange wings 19 are provided near their outer extremities with holes 22 each of which permits the passage of a securing screw indicated in dotted lines at 23 of Fig. 2, two of these screws being used to secure the support to the telephone casing. The channel portion 20, serves as a stiffening rib for the support to make it rigid and inflexible even though very light and inexpensive stock be used in its manufacture.

The flange portion 21 is made, having a considerable width and is adapted to be centrally placed on the bottom of the cup member 16, the bottom of the cup and the contacting portion of the flange being held

flatly together, and while so held they are spot-welded in the ordinary way for spot-welding together two flat pieces of steel, or the like, of which my improved support 5 would preferably be constructed. After the two parts of the support have been electrically welded together, they are then finished, preferably by enameling.

The application of the support of my invention to the wall telephone is now obvious. The dial is held in place and secured to the cup by means of a plurality 10 of holes located on the side wall of the cup, and co-operating projections on the dial 15 frame, the dial and cup being secured together by means of a machine screw passing through one of the holes in the cup and engaging a theraded portion in the said dial frame; or the dial or cup may be secured 20 together in any other suitable way, as is the common practice in this art, where the dials are mounted on the edge of circular walls as is the case here.

Having thus described my invention, I 25 do not intend to limit the same by the specific embodiment thereof, herein illustrated and described, but what I claim as my invention, is defined in the following claims.

I claim:—

30 1. In an automatic telephone dial support the combination with a metallic dial supporting cup, of a sheet metal support for the said cup, said support having an intermediate longitudinal rib, flanges for the 35 said support at either end thereof, one of the said flanges being disposed in a plane different to that of the other flange, the plane of one of the said flanges being parallel to the longitudinal rib, said last named flange being 40 rigidly secured to the bottom of the said cup.

2. In an automatic telephone dial support, the combination with a metallic dial supporting cup, of a sheet metal support 45 for the said cup, said support having an intermediate longitudinal rib, flanges for the said support at either end thereof, one of the said flanges being disposed in a plane different to that of the other flange, the 50 plane of one of the said flanges being parallel to the longitudinal rib, said last named flange being rigidly secured to the bottom of the said cup, a telephone casing, and means to secure the said support to a bottom 55 wall of the said casing at a point adjacent an edge thereof, said means comprising the other end flange, said rib, said casing wall and the bottom of the said cup forming a substantially closed channel to protect 60 an electrical circuit conductor placed in the said channel leading from the interior of the said casing to the interior of the said cup.

3. In a telephone set, a dial, a support

for said dial having one end circular, and 65 having a neck extending from the circular section, and a cross-arm connected to the other end of said neck, said dial attached to one end of said support, and the other end of the support attached to the telephone 70 set, said cross-arm having a flat surface and said circular section having a flat surface, said cross-arm and said circular end so related that a plane parallel to said circular surface is inclined at an angle to a plane 75 parallel to said cross-arm surface.

4. In a telephone set a dial, a support for 80 said dial, said support made of a flat piece bent to form two planes, said support having one end circular, a neck extending from 85 said circular section and a cross arm connected to the other end of said neck, one of said ends of said support secured to the telephone set, and said dial secured to the other end of said support.

5. In a telephone set a dial, a support 90 for said dial, said support made of a flat piece bent to form two planes, said support having one end circular, a neck extending from 95 said circular section and a cross arm connected to the other end of said neck, one of said ends of said support secured to the telephone set, and said dial secured to the other end of said support, said circular section in one of said planes and said cross arm in the other of said planes.

6. In a telephone set a dial, a support 100 for said dial, said support made of a flat piece bent to form two planes, said support having one end circular, a neck extending 105 from said circular section and a cross arm connected to the other end of said neck, one of said ends of said support secured to the telephone set, and said dial secured to the other end of said support, said cross-arm in 110 one of said planes, and said neck in the other of said planes.

7. In a telephone set a dial, a support for 110 said dial, said support made of a flat piece bent to form two planes, said support having one end circular, a neck extending from 115 said circular section and a cross arm connected to the other end of said neck, one of said ends of said support secured to the telephone set, and said dial secured to the other end of said support, said neck and said circular section both in the same one of said planes.

8. In a telephone set, a dial, and a support 120 for said dial comprising a cup member to receive said dial, and a neck formed from a single piece having one end flanged to receive said cup member, and the other end flanged and attached to said telephone set.

In witness whereof, I hereunto subscribe 125 my name this thirteenth day of October,
A. D. 1919.

ARTHUR J. CURREN.
